UNITED STATES PATENT OFFICE.

JOHN MUSSER, OF FRIZELLBURG, MARYLAND.

IMPROVEMENT IN FLOUR-PACKERS.

Specification forming part of Letters Patent No. 55,885, dated June 26, 1866.

To all whom it may concern:

Be it known that I, JOHN MUSSER, of Frizellburg, Carroll county, State of Maryland, have invented a new and useful Machine for Filling and Packing Bark, Guano, &c., in Bags or Casks; and I do hereby declare the following to be a clear and exact description thereof, reference being had to the accompanying drawings, and to the letters of reference marked thereon, making a part of this specification.

The nature of my invention consists in stampers with movable levers arranged in combination with a revolving cylinder that holds the bag or cask to be filled with bark or guano.

Figure 1 represents a front elevation; Fig. 2, a side elevation.

A is the upright frame that supports the operating devices; B, a horizontal shaft to be driven by a crank or band wheel, having four projecting arms, C, and bevel-gearing D.

The arms C operate upon the movable levers E, that operate the upright stampers G, while the level-gearing D drives the belt H, that revolves the upright cylinder J, that holds the

bag or cask K, that revolves with the cylinder J, while the stampers stamp the bark or guano around the side instead of in the center of the bag.

When the bag is stamped full the bevel-wheel D on the post L is pushed aside and un-gear'd, and the cylinder ceases to revolve until the filled bag is removed and another bag replaced to be filled and stamped tightly; and at any time that it is necessary to stop the operation of the stampers the lever M is raised and the hooks N N hold up the movable levers E.

What I claim as my invention, and desire to secure by Letters Patent, is—

The movable levers E, operating on the vertical stampers G, with the upright revolving cylinder J, when arranged, combined, and operated as herein described, and for the purposes set forth.

JOHN MUSSER.
